(57) **CLAIM**

The ornamental design for a space-saving computer keyboard layout, as shown and described.

DESCRIPTION

FIG. 1 is a top plan view of one embodiment of a computer keyboard constructed in accordance with the invention; FIG. 2 is a front elevational view of the keyboard of FIG. 1; FIG. 3 is a rear elevational view of the keyboard of FIG. 1; FIG. 4 is a left side elevational view of the keyboard of FIG. 1;

FIG. 5 is a right side elevational view of the keyboard of FIG. 1;

FIG. 6 is a bottom plan view of the keyboard of FIG. 1; and, FIG. 7 is a top front right isometric view of the keyboard of FIG. 1.

The broken lines are shown in the views for illustrative purposes only and form no part of the claimed design.
